TRIPLE SWIVEL

Sinnet Charles, Welch, W. Va., assignor of one-half to Milton B. Crisp, Welch, W. Va.

Application April 22, 1947, Serial No. 743,098

3 Claims. (Cl. 287—91)

1

The present invention relates to multiple swivels of a type in which the structural device, as a unitary assemblage, is bodily turnable and which includes independent eyes or equivalent elements, these being turnable on their own axes.

More specifically, the invention appertains to a so-called triple swivel characterized by a headed main or principal eye, and a pair of complementary independent eyes, the latter in the form of elongated links, and said last named eyes being swivelly mounted on a hub member carried by the headed portion of the principal eye.

The object of the invention is to structurally, functionally and otherwise improve upon three way swivels of the class under consideration by providing an adequate and complete construction which is possessed of requisite simplicity, durability, reliability and equivalent functions so necessary in appropriate handling of a plurality of rigging ropes or the like to minimize relative twisting and snarling of said ropes.

Another object of the invention is to provide a triple eye swivel construction employing both circular and elongated eyes, the same being interrelated to facilitate proper coaction of same when employed in the logging industry, or whenever necessary when handling loads for dragging, lifting and where relative axial turning of the independent ropes or lines is necessary to overcome the likelihood of independent intertwining and snarling of said ropes.

Other objects and advantages of the invention will become more readily apparent from the following description and the accompanying illustrative drawings.

In the drawings, wherein like numerals are employed to designate like parts throughout the views:

Figure 1 is an elevational view, partly in section, showing a triple swivel constructed in accordance with the principles of the present invention;

Figure 2 is a fragmentary sectional and elevational view taken on the plane of the line 2—2 of Figure 1, looking in the direction of the arrows; and,

Figure 3 is a perspective view of one of the elongated eyes or so-called links.

Referring now to the drawings by distinguishing reference numerals, the forementioned principal eye or primary part, forming the nucleus for the other parts, is denoted by the numeral 5. This is a metal eye of any appropriate circular

2

or ring-like form as indicated at 6, the same having a lateral pin or shank 7 projecting from one peripheral side. The shank adjoins the eye proper by way of a circular abutment shoulder 8 and the outer end of the shank is provided with a shoulder forming head 9. The shoulder is spaced apart to accommodate a ring 10 which is a part of the assembling hub means. The latter also includes a pair of diametrically opposite shanks, 11 and 12 and being of general L-shaped form and terminating in shoulder forming heads 13. The headed ends serve to accommodate annular collar portions 14 on the elongated eyes or so-called links 15 and 16. The numerals 17 designate loose fitted spacing collars interposed between the collars 14 and the laterally bent portions of the headed studs 11 and 12. The studs are such as to project outwardly beyond the head 9 in order to position the main ring or eye 6 on-center and the links 15 and 16 off-center.

It is obvious that the entire device, its parts clustered together as shown and described, is bodily turnable in a unitary sense and that all of the three eyes are, in addition, independently turnable or rotatable on their respective axes. Thus, in load handling ropes, chains and equivalent riggings, three independent lines or ropes may be accommodated, one attached to each eye. Moreover, when thus connected together the ropes will have sufficient independent axial movements to, under ordinary circumstances, permit required freedom and to prevent undesirable entwining and bothersome tangling.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

What I claim is:

1. A triple swivel construction of the class described comprising a ring adapted to function as a hub, said ring being provided at diametrically opposite points with integral L-shaped headed studs, collars surrounding the studs, said collars serving as spacers, a pair of links, each link being provided with a fixed assembling and swivelling collar, said swivelling collar links being mounted on the headed ends of said studs.

2. A triple swivel construction of the class described comprising a ring adapted to function as a hub, said ring being provided at diametrically opposite points with integral L-shaped headed studs, collars surrounding the studs, said collars serving as spacers, a pair of links, each link being provided with a fixed assembling and swivelling collar, said swivelling collars links being mounted on the headed ends of said studs, and an eye having a double shouldered shank, 10 said ring surrounding the shank at points between the shoulders.

3. In a triple swivel construction of the class shown and described, a principal eye provided on one side with an outstanding shank, said shank having longitudinally spaced shoulders, a hub forming ring rotatably surrounding said shank and retained swivelling in place between the stated shoulders, said ring being provided on diametrically opposite sides with a pair of outstanding L-shaped headed studs, the headed ends 20 of the long limbs of said L-shaped studs extending beyond the outermost shoulder on said shank,

a pair of elongated complementary links provided at corresponding ends with swivelling collars, said swivelling collars being mounted on the headed ends of the L-shaped studs, and spacing collars also mounted on said L-shaped studs, confined to retention on the long limbs of said studs and abutting the coacting short limbs of the respective studs.

SINNET CHARLES.
